Chester S. Brantton

Attorney

UNITED STATES PATENT OFFICE.

ALVIN E. BUCHENBERG, OF TOLEDO, OHIO, ASSIGNOR, BY MESNE ASSIGNMENTS, TO THE ELECTRIC AUTO-LITE COMPANY, OF TOLEDO, OHIO, A CORPORATION OF OHIO.

CONNECTER.

Application filed September 9, 1918, Serial No. 253,262. Renewed April 29, 1926.

This invention relates to improvements in connecters for wire terminals.

An object of the invention is to provide a connector which is particularly adapted for terminals of wires used as electrical conductors.

Another object of the invention is to provide such a connector, whereby a neat and strong connection can be expeditiously made with the terminal of a wire.

Yet another object of the invention is to provide a connector as above characterized, which, when connected to a wire, obviates any possibility of the same becoming disconnected.

Further objects of this invention relate to economies of manufacture and details of construction as will hereinafter appear from the detailed description to follow. I accomplish the objects of my invention in one instance by the devices and means described in the following specification, but it is evident that the same may be varied widely without departing from the scope of the invention as pointed out in the appended claims. A structure constituting one embodiment of my invention, which may be the preferred, is illustrated in the accompanying drawings forming a part thereof, in which:

Figure I is a plan view of a stamped blank shown in side elevation and constituting the initial form of the connector.

Figure II is a view similar to Figure I and shows the wire holding portion of the connector, formed for the insertion of a wire.

Figures III and IV are views similar to Figure II and illustrate the preferred manner of connecting the connector with the terminal of a wire.

Figure V is a transverse section on the line V—V of Figure IV, and

Figure VI is a perspective view of the connector as shown in plan in Figure II.

Referring to the drawings, a plate or blank 10 is provided, comprising a holding portion 11 and a connecting portion 12 (Figure I). A central opening 13 is provided in the connecting portion 12, adapted to receive the screw post or other means to which this portion of the connector is to be secured. The portion 12 is approximately circular in shape, and, with respect to the length

of the connector, has its sides cut away as indicated at 14 and 15. The connecting portion 12 is further provided with radial grooves which are stamped in the bottom face of the portion and thus providing the raised surfaces 16 on its upper face. The advantages of these raised surfaces 16 are well known in the art and a statement relative thereto is unnecessary.

In the portion 11 of the blank or plate 10 there are provided slit-like openings, indicated by the lines 17 and 18, whereby wing sections 19 and 20 are provided. This is preferably done by stamping.

The wing sections 19 and 20 will be hereafter referred to as inner wings and the portions between the longitudinal edges and the dotted lines 21 and 22 of the connecting portion 12 will be referred to as the outer wings 23 and 24, respectively. In Figure II, I have shown the inner wings 19 and 20 bent inwardly, so that their longitudinal edges are disposed in spaced relation for receiving a wire between them. Also, the outer wings 23 and 24 are bent inwardly to correspond to a plane substantially perpendicular to the connecting plate portion 12, as clearly illustrated in Figure VI.

When it is desired to secure the connector to the terminal of the wire, the insulation is removed from the terminal which is then inserted between the inner wings to the connector and the said wings are then bent downwardly upon the wire, as illustrated in Figure III. The wire 25 in this particular instance is of the flexible type, comprising a plurality of strands. It is to be understood, however, that a single strand wire may be used equally as well. As shown in Figure V, the strands are spread and flattened so that a greater area of contact is had between the wires and holding portion 11 of the connector, whereby the resistance to flow of current is lessened, and the possibility of heating eliminated. This may be taken advantage of in dispensing with the use of solder and obtain a great saving in electric wiring. Also, this feature is of an advantage in securing a better grip upon the wires against slipping. After the bared end of the wire has been secured by the inner wings 19 and 20, the wire is bent reversely to lie above the inner wings 19 and between the outer wings 23 and 24. The

outer wings are then clamped down on the wire thus completing a close contacting and secure grip between the connector and wire.

In the above description and the accompanying drawings, I have described and shown my invention when used as a connector for terminals of electrical conductors. It is to be understood however, that my invention is applicable to other uses with equal efficiency, and is not to be limited, as herein shown and described.

Having thus described my invention, what I claim as new and desire to secure by Letters Patent, is:

15 1. A terminal for an electric conductor comprising a plate having a pair of integral wings adapted to be folded over from opposite sides in one direction to bind said conductor against said plate and a second pair 20 of integral wings adapted to be similarly folded over to bind another part of said conductor against said first mentioned wings.

2. A terminal for an electric conductor comprising an apertured portion and a conductor engaging portion, said latter portion having an inner pair of oppositely positioned wings adapted to be folded in one direction to engage one part of said conductor and having an outer pair of oppositely positioned 30 wings adapted to be folded in the same di-

rection to engage another part of said conductor to bind it against the outer faces of said first mentioned pair of wings.

3. A terminal for an electric conductor comprising a metallic plate having a binding 35 post attaching portion and a conductor attaching portion, the latter portion comprising a central body portion having wings extending laterally from opposite sides thereof, each of said wings having stamped therefrom a second wing, said second wings being bent to clamp jointly one part of said conductor against said body portion and the remaining portions of said first mentioned wings being bent to clamp jointly another 45 part of said conductor against said second wings.

4. A terminal for an insulated conductor having a bared end portion comprising a plate having wings extending laterally from opposite sides thereof, each of said wings having a second wing punched from the body thereof, said second wings being folded to clamp the bared end of said conductor against said plate and said first wings being 50 folded to clamp an insulated portion of said conductor against said second wings.

In testimony whereof, I affix my signature.

ALVIN E. BUCHENBERG.
